UNITED STATES PATENT OFFICE.

ALBERT S. RICHARDSON AND CLINTON V. CONLEY, OF CINCINNATI, OHIO, ASSIGNEES
TO THE PROCTER & GAMBLE COMPANY, OF CINCINNATI, OHIO, A CORPORATION OF
OHIO.

PROCESS FOR DECOMPOSING FATS OR OILS INTO FATTY ACIDS AND GLYCERIN.

No Drawing.

Application filed March 13, 1922. Serial No. 543,514.

The objects of our invention are to decrease the amount of impurities present in the fatty acids obtained by the decomposition of fats or oils and also to cheapen the 5 operation by the substitution of less expensive reagents for those previously used in the process.

The nature of our invention can be best understood by reference to the prior operation 10 which our new process is intended to replace. It has been common practice to carry out the reaction between fats or oils and water to form fatty acids and glycerin, a reaction known as the hydrolysis of fats or 15 oils, by bringing together the reacting substances, at a suitable temperature and with provision for mixing either by steam or by mechanical stirring, in the presence of relatively small quantities of mineral acids and 20 of organic sulfonic acids known as "saponifiers", "emulsifiers", "splitting agents", etc.

The saponifiers used in past practice have consisted in large part of fatty-aromatic-sulfonic acids, which are prepared by the action 25 of sulfuric acid on a mixture of unsaturated fatty acids, e. g., oleic acid, and aromatic hydrocarbons, e. g., benzene, naphthalene, or cymene. Also, there have been used as saponifiers sulfonic acids of petroleum hydrocarbons of high molecular weight, comparable 30 with the high molecular weight of the fatty-aromatic-sulfonic acids. For example, Petroff, describing a process for the preparation of sulfonic acids of petroleum oils, states that "all these have a molecular weight higher than 250". Of correspondingly high molecular weight are the proposed saponifiers prepared by the sulfonation 35 of high boiling hydrocarbons from lignite tar, coal tar, peat tar, and bituminous minerals, such as "anthracene oil" or "solar oil" of specific gravity 0.8621.

It has been commonly supposed that the sulfonic acids of aromatic hydrocarbons such 45 as benzene, or naphthalene, or their simple derivatives of relatively low molecular weight, such as toluene, or cymene, are not active as saponifiers. We have found, however, that the sulfonic acids of the simple aromatic hydrocarbons, such as occur in nature or are readily obtained by the thermal decomposition of naturally occurring products, are in fact active as saponifiers,

even when such sulfonic acids have molecular weights well below 250. Even benzene sulfonic acid has an appreciable activity, although the activity of the sulfonic acids of aromatic hydrocarbons containing no aliphatic side chains (for example, benzene or naphthalene) is relatively slight. The activity 55 of the saponifier is greatly increased if the molecule of the aromatic hydrocarbon contains one or more aliphatic side chains. Thus the sulfonic acids of toluene and of the xylenes are considerably more active 60 than benzene sulfonic acid, while the sulfonic acids of the higher boiling liquid hydrocarbons obtained from coal tar solvent naphtha are still more active. Also the sulfonic acid of cymene, a hydrocarbon occurring 65 in spruce turpentine, is quite active.

As compared with the saponifiers hitherto employed, our saponifiers have the advantage of greater purity and of lower cost.

Mineral acids, e. g., sulfuric acid, when 75 used in conjunction with our saponifiers produce a more rapid reaction and in this respect are of considerable advantage. However, such mineral acids are not essential 80 and have the disadvantage of producing fatty acids of darker color.

During hydrolysis the saponifiers hitherto employed dissolve chiefly in the fatty layer, even though possessing a considerable degree of water solubility in the absence 85 of fatty matter. On the contrary, our saponifiers dissolve chiefly in the aqueous layer and wholly so if the concentration of mineral acid is not greater than 4% of sulphuric acid. Since, moreover, the rate 90 of hydrolysis of fats increases rapidly with increasing concentration of water soluble saponifiers, the relative proportion of water and saponifier used in our process is particularly important. It is desirable at 95 all times to restrict the quantity of water present to the minimum amount necessary for the reaction. In other respects, the operation of hydrolyzing fats with our saponifiers does not differ in any essential 100 from the well known and widely practiced operation as carried out with other saponifiers.

Examples.—100 parts of tallow, 2½ parts of cymene sulfonic acid, and 20 parts 105 of water were heated to 100° C., and

mechanically agitated. In five hours the free fatty acid increased from 5.5% to 75.4% of the total fatty acid content of the tallow. 100 parts of similar tallow, treated as above except for the addition of one part of 66° Bé. sulfuric acid, contained free fatty acids to the extent of 80.7% of the total fatty acids after five hours, but the product was more darkened. The fats or oils hydrolyzed in this way can be used directly for purposes which require a high free fatty acid content. If higher free fatty acid content is desired, the reaction can be continued with the addition of more water and the partially hydrolyzed fat can then be given a second saponification treatment, in which case the resulting water layer is used for the first treatment of fresh fat.

Having thus described our invention,

what we claim as new and desire to secure by Letters Patent, is:—

1. The process of decomposing fats or oils into fatty acids and glycerin by reaction with water, which consists of heating and agitating the reaction substances in the presence of aromatic sulfonic acids of molecular weight less than 250 without the use of oleic or similar fatty acid, substantially as described. 30

2. The process of decomposing fats or oils into fatty acids and glycerin by reaction with water, which consists of heating and agitating the reacting substances in the presence of aromatic sulfonic acids of molecular weight less than 250 without the use of oleic or similar fatty acid, together with sulphuric acid, substantially as described. 35
